United States Patent Office

Des. 198,174
Patented May 12, 1964

198,174

GOBLET OR SIMILAR ARTICLE

Howard Treu, 52 Riversville Road, Greenville, Conn.

Filed Mar. 27, 1963, Ser. No. 74,166

Term of patent 3½ years

(Cl. D36—8)

FIG. 1 is a front elevational view, partly in section, of a goblet or similar article, showing my new design. FIG. 2 is a section, taken on the line 2—2 of FIG. 1. FIG. 3 is a section taken on line 3—3 of FIG. 1.

I claim:

The ornamental design for a goblet or similar article, as shown.
